CLAIM

We claim the ornamental design for a cosmetic brush, as shown and described.

DESCRIPTION

FIG. 1 is a top, front isometric view of a cosmetic brush. FIG. 2 is a front elevation view of the cosmetic brush of FIG. 1.

FIG. 3 is a rear elevation view of the cosmetic brush of FIG. 1.

FIG. 4 is a right side elevation view of the cosmetic brush of FIG. 1.

FIG. 5 is a left side elevation view of the cosmetic brush of FIG. 1.

FIG. 6 is a top plan view of the cosmetic brush of FIG. 1; and,

FIG. 7 is a bottom plan view of the cosmetic brush of FIG. 1.

The dash-dash broken lines illustrate unclaimed portions of the cosmetic brush and form no part of the claimed design. The dash-dot-dash broken lines represent unclaimed boundaries of the design.

Any combination of the illustrated features, including claimed features and non-claimed features, may be claimed in this application or in a continuing application claiming priority to this application by converting any portion of the broken lines to solid lines, any portion of the solid lines to broken lines, deleting any of the broken lines representing a boundary, or any combination thereof.
